GROSVENOR N. ALLEN, OF ONEIDA, NEW YORK, ASSIGNOR TO ONEIDA COMMUNITY, LIMITED, OF ONEIDA, NEW YORK, A CORPORATION OF NEW YORK.

DESIGN FOR A HANDLE FOR SPOONS, FORKS, OR SIMILAR ARTICLES.

40,840.

Specification for Design.

Patented Aug. 30, 1910.

Application filed June 7, 1910. Serial No. 565,662. Term of patent 14 years.

To all whom it may concern:

Be it known that I, GROSVENOR N. ALLEN, a citizen of the United States, residing at Oneida, in the county of Madison, State of New York, have invented a new, original, and ornamental Design for a Handle for Spoons, Forks, or Similar Articles, of which the following is a specification, reference being had to the accompanying drawing, forming a part thereof.

The design consists in the form and ornamentation of the handle portion of a spoon.

The essential feature of this design consists in the marginal ornamentation, as shown upon the handle of the spoon, confined between two slight beads or raised portions.

I claim:

The original design for a handle for spoons, forks or similar articles as shown and described.
